BRASSIÈRE TOP

Ruth F. Peck, Minneapolis, Minn., assignor to
 Winget Kickernick Company, Minneapolis,
 Minn., a corporation

Application August 29, 1936, Serial No. 88,477

5 Claims.

(Cl. 2—73)

My invention relates to brassière tops and has for its object to provide a brassière top which may be separately worn but also which may be worn in combination with a skirt portion, which 5 shall be particularly comfortable in wear, which shall give requisite and adequate support for the breasts, which shall provide means to hold it correctly in position on the form of the wearer, and which shall eliminate any placket or side opening 10 customarily employed and heretofore thought necessary in brassière tops.

It is a particular object of my invention to provide a brassière top with fastening members embodying in part at least elastic material adapted 15 to go to the back of the wearer under the brassière top and to be separated and secured together after the garment has been drawn over the upper part of the wearer's form and which thus will permit the brassière top to be taken on 20 and off without the need of any opening or placket either at the side or back of the brassière top.

It is also an object of my invention to provide the separate holding devices above referred to 25 at the back of the garment and to be beneath the back of the brassière top when worn and to have the effect of causing the brassière top to hold the busts in a proper position so as to overcome their sagging or hanging-down tendency.

30 My invention accomplishes these results either in a separate brassière top or in a combination garment, not only with the above stated advantages as to elimination of all plackets or openings which require to be fastened with buttons or 35 snaps, and which enables the brassière top to hold the busts properly positioned, but also gives a combination garment which will be accurately form-fitting in its upper portion and from which the skirt portion will hang effectively either directly 40 from the upper portion of the brassière top or from a waistband connection therewith.

The full objects and advantages of my invention will appear in connection with the detailed 45 description thereof, and the novel features are particularly pointed out in the claims.

In the drawing, illustrating an application of my invention in one form,—

Fig. 1 is a rear view of a combination garment 50 embodying the improvement of my invention as it appears on a feminine figure. Fig. 2 is a similar front view of such a garment. Fig. 3 illustrates the brassière top in position on the form of a wearer in combination with a waist portion but without the skirt portion directly formed 55 therewith. Fig. 4 illustrates the brassière top

shown in Fig. 3 when turned inside out and from a back view. Fig. 5 is a section through the garment taken in the plane through the busts and the rear fastening members. Fig. 6 illustrates in plan or pattern form the parts of the garment 5 which are united with the bust forms to provide the back support for the brassière top. Fig. 7 shows such a support made of tapes only. Fig. 8 is a detail view of the back supporter members.

As illustrated, the brassière top embodies rear 10 sections 10 and 11, as in Fig. 1, or a single rear section 12 as in Fig. 4; also front section pieces 13 and 14 as in Fig. 2, which may be united with an angular member 15 connected with the skirt portion 16 as in Fig. 2 or which may embody a 15 single front member 17 as in Figs. 3 and 4. United with the front portions 13, 14, 15 of Fig. 2, or 17 of Fig. 3, are bust forms 18 and 19 formed of net or other desired material and of well-known construction.

Secured to the sides of the bust forms 18, 19 are supporting members 20 and 21 of the general substantially triangular shape shown in Fig. 6. These members are independent of the body of the brassière top and are set under the brassière top as indicated in dotted lines at 22 in Fig. 1, at 23 in Fig. 2 and at 24 in Fig. 3. The edges 25 and 26 of members 20 and 21 which are attached to the bust forms are curved as shown. The short edges 27 and 28 of members 20 and 21 are at the 30 top and the long edges 29 and 30 are at the bottom. In place of the united members 20 and 21 tapes or a continuous tape having a long base portion 31 and shorter top portions 32 and 33 may be employed in which the longer tape portion 31 will encircle the body of the wearer, being secured to the bust form proper in the area indicated at 34 within the dotted lines of angular member 15, and the tape portions 32 and 33 being secured to the top sides of the brassière tops 18 40 and 19 at the point shown in dotted lines at the joiner of the upper dotted lines shown in Figs. 1, 2 and 3.

In the form of supporting members illustrated in Fig. 6 elastic tapes 35 and 36 are secured to 45 the pointed ends of members 20 and 21, as shown in Fig. 6, where the back of the brassière top is broken away in Fig. 1, and also in Fig. 4.

The fold of elastic tape 35 and the corresponding end 37 of the tape members 31, 32 (which 50 also are preferably of elastic material) is provided with a flat eye-piece 38 having a slotted eye 40 open at one edge as indicated at 41. The loop of the fold 35 is slipped down through the opening 41 into the eye slot 40 when the garment is se- 55

cured in position upon the form of the wearer. Or, if the tapes are employed, a loop 38 formed between tape portions 31, 33 is similarly slipped into the slot 46 through opening 41 to secure the 5 garment in position upon the form of the wearer.

The length of the supporting members 20 and 21 under the brassière top formed of portions 10, 11, 13 and 14, or 12 and 17 is such that when the loops are united by means of the flat eye-piece 48, the elastic members will be somewhat stretched and will hold the supporting members through 21 or, as tapes, 31, 32, 33, under tension on the body. Because of the connections of these supporting members with bust forms 18 and 19 15 there will result a holding of the bust forms firmly in fixed position so as to resist any tendency of the weight of the busts in said bust forms to sag or hang down. In other words, the brassière top will be firmly and suitably held about 20 the form of the wearer, and at the same time no placket or opening anywhere along the brassière top either at the sides or at the back will be employed. The garment, whether a combination garment as in Figs. 1 and 2 or a brassière top 25 only as in Figs. 3 and 4 will be supported from the shoulders of the wearer in a well-known manner by straps 42 and 43.

The advantages of my invention have been given in the detailed description heretofore presented. While providing a brassière top adapted to hold the bust forms very firmly in position to give adequate support to the busts therein, there is no placket or opening in the brassière top and no pulling or lines from the fastening of such a 35 placket, and the entire garment all about the body is smooth and free from folds or lines of any sort. It is thus particularly adapted to provide a foundation for outer garments of a thin and sheer character. At the same time the garment 40 is easily removed from the form of the wearer, and, hence, is convenient in use.

I claim:

1. A slip embodying brassière top having bust forms and having no plackets or openings to be 45 fastened together for putting the garment on and off, a pair of substantially triangular members each embodying a wide curved edge sewed to an outer edge of one of the bust forms and adapted to encircle the sides and back inside of the brassière top and waist portion, and means for removably attaching the free ends of said members under the brassière top.

2. A slip embodying brassière top having bust forms and having no plackets or openings to be fastened together for putting the garment on and off, a pair of substantially triangular members each embodying a wide curved edge sewed to an outer edge of one of the bust forms and having the long bottom edges adapted to encircle the side and back portions of the body of the wearer in a plane substantially normal to the axis of the body inside the brassière top and 10 waist portion, and means for removably attaching the free ends of said members under the body of the brassière top. 5

3. A brassière top having bust forms and having no plackets or openings to be fastened together 15 for putting the garment on and off, straps for holding the same suspended from the shoulders, a pair of members having spaced points of attachment with the bust forms and extending under the brassière top to the center of the back, 20 said members each including elastic material, and means for removably attaching the free ends of said members under the body of the brassière top at the back so as to hold the bust forms firmly under distributed tension. 25

4. In a form-fitting slip of non-elastic material, a brassière top having bust forms and having no plackets or openings to be fastened together for putting the garment on and off, a back portion to the garment, straps connected 30 with the bust forms and with said back portion for holding the garment suspended from the shoulders, non-elastic members directly connected with said bust forms and underlying the back, and means removably securing said non- 35 elastic members together to hold the bust forms firmly under distributed tension.

5. In a form-fitting slip of non-elastic material, a brassière top having bust forms and having no plackets or openings to be fastened to 40 together for putting the garment on and off, a back portion to the garment, straps connected with the bust forms and with said back portion for holding the garment suspended from the shoulders, non-elastic members directly connected with said bust forms and underlying the 45 back, and means including short sections of elastic tape removably securing said non-elastic members together to hold the bust forms firmly under distributed tension. 50

RUTH F. PECK.
